UNITED STATES PATENT OFFICE.

JOHN H. SCHEIBELER, OF NEBRASKA CITY, NEBRASKA.

FLUSH-TANK VALVE.

Application filed April 29, 1925. Serial No. 26,699.

The invention relates to flush tank valves, and has for its object to provide a device of this character comprising a flexible member connected to one side of the discharge 5 end of the intake pipe and provided with a disc having an inclined surface inclined towards a bracket to which is pivotally connected a float controlled bar, which bar terminates in a hooked cam member, which engages the inclined surface of the disc, and when the float is in raised position within the tank forces said flap valve into close binding engagement with the end of the intake pipe, thereby cutting off the flow of water 10 to the tank, and positively holding the valve in closed position. The valve obviates the use of ground valves and seats, therefore leakage is prevented.

With the above and other objects in view 20 the invention resides in the combination and arrangement of parts as hereinafter set forth, shown in the drawing, described and claimed, it being understood that changes 25 in the precise embodiment of the invention may be made within the scope of what is claimed without departing from the spirit of the invention.

In the drawing:

Figure 1 is a vertical sectional view 30 through a portion of a conventional form of flush tank, showing the valve applied to the intake pipe thereof.

Figure 2 is a perspective view of the valve.

Figure 3 is a vertical longitudinal sectional view through the valve.

Referring to the drawing, the numeral 1 designates a conventional form of flush valve tank, into which the water supply or intake pipe 2 extends. Secured to the upper end of the water supply pipe 2 is a sleeve 3 forming an extension of the intake pipe, which sleeve has its upper end provided with an annular flange 4, the upper side of which is provided with a valve seat 5. Secured to the annular flange 4 adjacent one side thereof at 6 is a flexible flap valve 7, which flap valve has its upper side 8 provided with a disc 9. The disc 9 has its upper face 10 inclined downwardly towards the upwardly extending bracket 11 carried by the flange 4, and when forced downward-

ly forces the flap valve 7 into close binding engagement with the valve seat 5 for preventing flow of water into the tank, however when the flap valve is released it will move upwardly rapidly, thereby allowing a maximum flow of water into the tank and causes the tank to rapidly fill. As the level of the water within the tank 1 rises the float 12 is raised and the float arm 13 is rocked on its pivotal point 14, thereby forcing its hooked cam member 15 downwardly in engagement with the upper inclined surface 10 of the disc 9, consequently the flap valve 7 will be closed and the flow of water to the tank will be cut off, however when the float lowers a relatively large amount of water will be quickly discharged into the tank, thereby obviating objectionable noises as is now the difficulty with valves at present constructed.

It will be noted that the hooked cam member 15 of the arm 13 will limit the extent of opening of the valve by the engagement of said arm with a stop 16, therefore it will be seen that the valve 7 will open to an angular position in a plane at an acute angle to the valve seat 6, consequently the water which flows up through the supply pipe 2 will be deflected laterally into the tank, thereby preventing water from being projected against the top of the tank or above the tank.

From the above it will be seen that a flush tank supply pipe valve is provided, which is simple in construction, positive in its operation, and one which will give a maximum amount of flow of water during the tank filling operation in the minimum amount of time, and one wherein objectionable noises are obviated.

The invention having been set forth what is claimed as new and useful is:—

The combination with the intake pipe of a flush tank, of a horizontally disposed valve seat carried by the upper end of said intake pipe, an upwardly extending bracket at one side of the intake pipe and extending above the valve seat, of a flap valve hingedly connected to the upper end of the pipe at the opposite side thereof from the upwardly extending bracket, a disc carried by said

flap valve having an inclined surface, said flap valve cooperating with said valve seat, a float controlled rocker arm pivoted to the upper end of the upwardly extending bracket, a cam carried by the rocker arm and cooperating with said inclined surface of the disc and forming means for forcing

the flap valve into close binding engagement with the valve seat and for rapidly allowing the opening of the flap valve during an intake operation. 10

In testimony whereof I hereunto affix my signature.

JOHN H. SCHEIBELER.
